UNITED STATES PATENT OFFICE.

WARREN C. PATTERSON, OF TAMAQUA, PENNSYLVANIA.

DESIGN FOR A RAIL-CHAIR.

SPECIFICATION forming part of Design No. 29,105, dated July 26, 1898.

Application filed June 30, 1898. Serial No. 684,888. Term of patent 14 years.

To all whom it may concern:

Be it known that I, WARREN C. PATTERSON, a citizen of the United States, residing at Tamaqua, in the county of Schuylkill and State 5 of Pennsylvania, have invented a new and original Design for a Rail-Chair, of which the following is a specification.

This invention relates to a new and original design for a rail-chair; and it has for its 10 object to provide a design of this character that shall be both useful and ornamental.

The leading feature of the design resides in a rail-chair body having at one side edge of its base-plate a compoundly-curved upwardly-disposed flange provided at its opposite ends with substantially rectangular feet extensions projected laterally therefrom beyond the plane of the base-plate and flush with the lower side thereof.

20 A minor feature of the design resides in the compoundly-curved flange having swelled or thickened portions at the points where the feet extensions are projected.

In the drawings, Figure 1 is a perspective 25 view of a rail-chair embodying the herein-described design. Fig. 2 is a plan view thereof. Fig. 3 is a cross-sectional view on the line 3 3 of Fig. 2.

Referring to the accompanying drawings,

the numeral 1 designates a rail-chair body 30 having an approximately rectangular flat base-plate 2. This base-plate has projected upwardly from one side edge thereof a continuous longitudinal inturned curved flange 3, and at the side edge opposite the inturned 35 curved flange 3 is located an upwardly-disposed compoundly-curved flange 4, lying parallel with the flange 3, but of a greater width or elevation than the same. The said compoundly-curved flange 4 is provided at its 40 ends with swelled or thickened end portions 5, from which are projected the lateral substantially rectangular feet extensions 6. The feet extensions 6 project beyond one side of the chair-body and lie substantially within 45 the horizontal plane of the base-plate 2, and said extensions are provided therein with rectangular openings 7.

What I claim is—

The design for a rail-chair herein shown 50 and described.

In testimony that I claim the foregoing as my own I have hereto affixed my signature in the presence of two witnesses.

WARREN C. PATTERSON.
